UNITED STATES PATENT OFFICE.

RICHARD F. LE BROcq, OF NEW YORK, N. Y.

SAFETY DEVICE FOR ELEVATOR CARS AND DOORS.

1,120,724.

Specification of Letters Patent. Patented Dec. 15, 1914.

Application filed June 30, 1913. Serial No. 776,474.

To all whom it may concern:

Be it known that I, RICHARD F. LE BROcq, of the city of New York, county of Kings, and State of New York, have invented a new and useful Improvement in Safety Devices for Elevator Cars and Doors, of which the following is a full, clear, and exact description.

My invention relates to improvements in that class of devices which is used in connection with elevator doors and elevator controlling mechanism, so that a car cannot be started except when the door is closed. There have been many devices of this nature invented, but most of them are rather complex in structure, and some of them rely on electro-magnetic principles for at least a part of their action.

The object of my invention is to produce an extremely simple and reliable device, which can be readily applied to an ordinary elevator door and elevator car, and which by a purely mechanical connection between the door and car will cause the starting lever or controller of the car to be locked so that it cannot be moved when the door is opened, and will be automatically released when the door is closed.

In carrying out my invention, I do not rely on electrical devices of any sort, but have an attachment at each floor of a building which is connected with the door, and which will automatically connect with the lever or controller of the car as the car comes opposite a floor, so that the controller will be positively locked when the door is opened, and will be released when the door is closed, the general object being to prevent the starting of a car when the door is open, thereby preventing accidents such as frequently occur by reason of a person walking through an open door after the car has started.

Reference is to be had to the accompanying drawings forming a part of this specification, in which similar reference characters indicate corresponding parts in all the views.

Figure 1 is a broken sectional elevation of the mechanism which is applied to a car and controlling lever, the floor of the car being shown in dotted outline. Fig. 2 is a similar view taken at right angles to the view shown in Fig. 1. Fig. 3 is an enlarged broken detail plan of the sliding clutch which locks the shaft to which the lever or controller is

connected. Fig. 4 is a side elevation partly in section of the mechanism which is permanent on the wall of the elevator well and is connected to the sliding door. Fig. 5 is a cross section through the floor mechanism showing the connection between the door and the slide bar which actuates the car device. Fig. 6 is a detail end view of the contact or striking shoe at the end of the door actuated slide bar, and Fig. 7 is an enlarged detail side elevation of the slotted crank and the pin therein, the latter being struck by the shoe shown in Fig. 6.

Usually an elevator car is provided with a shaft 11 to which the lever 10 is attached, and by oscillating the lever and shaft, the mechanism for stopping and starting the car is controlled. I have not here shown this stopping and starting mechanism, as it has nothing to do with my invention, which relates to the means for locking and releasing the shaft 11 and the controlling lever 10. This shaft 11 is mounted on a suitable framework 12 which is secured beneath the floor of the car, and in Fig. 1 the floor of the car and the supports connecting with the frame 12 are shown in dotted outline. The structure of the frame and its connections is not material, however, as this varies with different styles of elevator cars. On the shaft 11 is a crank arm or lug 13 which can be secured in any convenient way, and this is arranged so that when the lever is in neutral position, that is in the position it assumes when the car is stationary, the lug 13 will be in position to be engaged by the sliding clutch 14, which is in the form of a forked plate, and which moves back and forth in a way 15 on the frame 12, and beneath a guide plate 16. When the sliding clutch 14 is pulled back to release the lug 13, the lever 10 and its shaft 11 may be turned freely, but when the clutch engages the lug 13, the aforesaid shaft and lever are locked.

The slide plate or clutch 14 is actuated by an arm 17 which is carried by a shaft 18, this being arranged at right angles to the shaft 11 and mounted in a suitable support in the frame 12, the shaft 18 being also at right angles to the path of the elevator door as will hereinafter appear, so that connections on the end of the shaft may be had with the mechanism connected with the door. The arm 17 enters the slot 19 (see Fig. 3) in the plate 16, and a recess

20 in the clutch or slide plate 14, so that the oscillation of the arm 17 will move the clutch or slide plate backward and forward, and a counter-weight 21 on the shaft 18 normally moves the clutch back so as to leave the lug 13 and shaft 11 free. Obviously the particular connection between the shaft 18 and the plate 14 is not material, and any suitable means can be used for actuating the slide plate or clutch by the oscillation of the shaft 18.

At the outer end of the shaft 18 is a bifurcated crank arm 22 which lies parallel with the wall of the elevator well, and in which is pivoted a dog 23, the latter being pivoted near its lower end as shown at 24 in Fig. 7, and having a projecting pin 25 which is rounded on its outer end for the purpose presently described, while the lower end of the dog 23 has an offset 23^a beneath which is arranged a spring 26 which normally throws out the pin 25. This causes the pin to extend into the path of a shoe 27 which is beveled on the sides near the upper and lower end as shewn at 28 in Fig. 6, and which has an eye 29 to receive one end of the slide bar 30, this being arranged in the wall of the elevator well, and beneath and parallel with the path of the elevator door 35. Obviously the shoe 27 can be attached to the slide bar in any convenient way, and can be either separate from the slide bar or integral therewith as desired. When the slide bar 30 is moved to the left from the position shown in Fig. 4, the shoe 27 strikes the pin 25, tilts the crank arm 22, and oscillates the shaft 18, thus actuating the clutch 14 in the manner already described. Ordinarily the pin 25 might well be rigid on the member 22, but there is a possibility that the door 35 might be forcibly held open some time when the elevator car was moving up or down, and in such case if the pin 25 were rigid on the member 22, it would strike the bar 30 or shoe 27, and something would have to break; but by having the pin 25 yielding and rounded at the outer end, in such case it would be forcibly pushed back and pass the bar and shoe without damage, and furthermore, in case the shoe 27 has, for the reason just stated, been pushed back past the pin 25, the bevel portions 28 would facilitate it to return. This is because the pin 25 would be likely to be in the path of the beveled portions of the shoe 27, so that they could readily slip by horizontally.

The bar 30 has a movement both longitudinal and vertical, and to this end it is mounted on rollers 32 which enter the incline slots 31 in the bar. These rollers are pivotally supported on the wall 33 of the elevator well, or in any convenient support, as shown in Fig. 5. The bar 30 is at the end nearest the door 35, bent as shown at

30^a, thus giving it a cam effect, and the bar is straddled by rollers 34^a which fit against the upper and lower edges of the bar, and are carried by a hanger 34 which is attached to the car door 35. It will be seen, therefore that when the door is opened, the rollers 34^a riding upon the incline 30^a of the bar 30, will force the bar downward, and the bar will slide down by reason of the incline slots 31, and also move backward for 75 the same reason. This forces the shoe 27 against the pin 25, tilts the crank 22 and shaft 18, thus actuating the slide block 14 and causing it to engage the lug 13 and firmly lock the shaft 11 and lever 10. When 80 the door is closed, the slide bar moves back to its first position by reason of the action of the rollers 34^a on the incline 30^a of the slide bar, the crank 22 is freed, and the weight 21 moves back the clutch or slide 85 plate 14, thus releasing the shaft 11 and lever 10.

From the foregoing description it will be seen that the structure which I have shown and described is extremely simple, that 90 there is a positive mechanical connection between the door and the controlling lever of the elevator when the elevator car is opposite a floor, that the car cannot be started except when the door is closed, and that 95 the structure is made in such a manner that there is no danger of breaking or disarranging any of the parts. It will further be noticed that the structure is such that no action is called for on the part of the car operator, who can only use his lever to stop 100 and start the car when the door is closed.

I claim:—

1. An apparatus such as described comprising a controlling lever on the car of an 105 elevator, a shaft connected with said lever, a lug on the shaft, a forked slide plate serving as a clutch to engage the aforesaid lug, a crank shaft operatively connected with the clutch to move it, a crank on the end of the 110 shaft near the wall of the elevator well, a longitudinally movable slide bar on the wall of the elevator well adapted to strike the aforesaid crank, a sliding door for the elevator, and an operative connection between 115 the door and slide bar whereby the movement of the door moves the slide bar.

2. In an apparatus such as described, the combination of the elevator car, the controlling lever thereon, the shaft extending along 120 the floor of the car to which the said controlling lever is attached, a crank shaft, a clutch operated by the oscillation of the crank shaft to lock and release the controlling lever shaft, a crank on the crank shaft located near the wall of the elevator well, a longitudinally movable slide bar on the wall of the elevator well, said slide bar having a shoe to engage the aforesaid crank, a sliding door for the elevator well, and an opera- 125 130 135

tive connection between the door and the slide bar whereby the movement of the door moves the slide bar.

3. An apparatus such as described comprising a slide bar on the wall of an elevator well, said slide bar having a guided vertical and longitudinal movement, and having an inclined portion thereon, a sliding elevator door, rollers carried by the door and engaging the slide bar, a crank shaft on the elevator car having its crank extending into the path of the slide bar, a controlling lever on the car, and means for locking and releasing the lever, said means being controlled by the oscillation of the crank shaft.

4. An apparatus such as described comprising an elevator car, a controlling lever on the car, a crank shaft on the car, a crank on said shaft arranged near the wall of the elevator well, means operated by the crank shaft to lock and release the controlling lever, a yielding pin projecting from the crank of the crank shaft, a slide bar in the elevator well having a shoe to engage the aforesaid pin, a sliding door for the elevator well, and means for operating the slide bar by the movement of the door.

5. A structure such as described comprising an elevator car, a controlling lever for the car, a crank shaft mounted on the car and having its crank near the wall of the elevator well, said crank shaft being connected with said controlling levers, a yielding pin mounted on and projecting from the crank of the crank shaft, a slide bar on the wall of the elevator well having a shoe at one end to engage the aforesaid pin, said slide bar having an inclined portion thereon, a sliding door, and rollers supported from the door and straddling the slide bar, whereby the movement of the rollers on the incline part of the slide bar moves the slide bar endwise.

6. A structure such as described comprising an elevator car, a shaft mounted on the car and provided with a lug, a controlling

lever connected with the shaft, a bifurcated slide plate or clutch arranged to engage the aforesaid lug, a weighted crank shaft on the car, the crank of the shaft being arranged near the wall of the elevator well, an operative connection between the crank shaft and the aforesaid slide plate, whereby the oscillations of the crank shaft move the slide plate, a sliding door on the elevator well, and means actuated by the door for engaging the crank of the crank shaft.

7. In a structure such as described, the combination with the elevator car, the controlling lever, the crank shaft having its crank near the wall of the elevator well, and means controlled by the oscillation of the crank shaft for locking and releasing the controlling lever, of a yielding pin on the crank of the crank shaft, a slide bar on the wall of the elevator well, a shoe on the slide bar to engage the aforesaid pin, said shoe having inclined upper and lower portions, a sliding door for the elevator well, and an operative connection between the door and the slide bar whereby the movement of the door moves the slide bar.

8. The combination with the elevator car, the controlling lever thereon, a crank shaft having its crank near the wall of the elevator well, and a locking device controlled by the movement of the crank shaft for locking and releasing the controlling lever, of a slide bar on the wall of the elevator well, said slide bar having inclined slots therein, rollers supported on the wall of the elevator well and entering said slots, a shoe on one end of the slide bar to engage the aforesaid crank, an inclined or cam portion on the slide bar, the sliding elevator door, and rollers carried by the door and engaging the upper and lower edges of the slide bar.
